PROCESS OF INCREASING THE INDUCTANCE OF A LOOP ANTENNA

Alphonse Charles Stelzer, Cincinnati, Ohio, assignor to Avco Manufacturing Corporation, Cincinnati, Ohio, a corporation of Delaware

Original application May 11, 1950, Serial No. 161,436. Divided and this application April 19, 1951, Serial No. 221,891

1 Claim. (Cl. 117—37)

1 The present invention is a division of my patent application Serial No. 161,436, filed May 11, 1950, now Patent 2,602,891.

The present invention relates to loop antennas and, without limiting the generality of the foregoing, particularly to the type employed in portable radio receivers and more specifically to a novel loop antenna the "L" of which is critically predetermined, and to a novel process for making the same.

In many radio receivers in which a loop antenna is included as a frequency-determining parameter in the antenna input circuit, which circuit is tuned as by a gang capacitor in tracking relationship to a local oscillator tank circuit, it is necessary to maintain the inductance (L) of the loop antenna within very close tolerances. In one well-known receiver of this type the first tube following the antenna is a pentagrid converter. A loop antenna paralleled by a variable section of a gang condenser is R. F. coupled between the third grid and cathode of this tube and an oscillator tank circuit, tuned by another variable section of this gang condenser, and a feedback coil are associated with various electrodes of the tube in a known manner. The two variable capacitor sections are ganged together. In receivers of this and similar types it is necessary to maintain the predetermined desired L of the loop within very close tolerances, and the present invention provides a novel loop in which this objective is achieved and a novel process for accomplishing it.

An object of the invention is to provide a loop antenna construction which precisely and rigidly adheres to a predetermined desired L characteristic.

Another fundamental object of the invention is to provide a novel process for adjusting the L of a loop within a narrow range of tolerances.

For a better understanding of the present invention, together with other and further objects, advantages, and capabilities thereof, reference is made to the following description of the accompanying drawings, in which there is shown a preferred illustrative form of loop antenna made in accordance with the present invention. In the drawings:

Fig. 1 is an illustration of a top view of a loop antenna in accordance with the invention;

Fig. 2 is a front view thereof; and

Figs. 3 and 4 are sectional views taken on lines 3—3 and 4—4 of Fig. 1, looking in the direction of the arrows.

The loop 10 is made of multistrand Litz wire

2 wound by conventional machinery into the desired loop configuration illustrated in Fig. 1, each successive turn of the loop being located radially outwardly from the preceding one so that the thickness of the loop is that of the single conductor. The wire is suitably insulated as by a thin plastic covering.

Preparatory to the winding process a suitable adhesive is applied to the conductor for purposes of securing the adjacent loop turns together. After drying the rigid loop is placed between two thin plastic Celluloid protective mounting members 11 and 12, each of which is slightly larger than the loop in area and is formed with a generally semicircular configuration to provide protective margins extending outwardly beyond the periphery of the loop. Each of the mounting members is preformed with a plurality of large apertures such as those indicated by the reference numerals 13, 14, 15, and 16, for a purpose to be explained hereinafter. Each of the mounting members is also preformed with suitable apertures to receive the terminal eyelets 17 and 18 to which the leads 19 and 20 are brought out. The mounting members are also provided with preformed small apertures 21, 22, 23, and 24, whereby the loop assembly may be secured to the lid of a portable radio receiver cabinet, for example, by conventional means. The assembly of loop and dielectric mounting members is secured together by strips of adhesive tape 25, 26, 27 interlocking with notches 28, 29, and 30 formed on the mounting members. It will be observed that the mounting members are identical and the same die may be employed to punch them out from the plastic dielectric material of which they are made.

In practical commercial operations, as will be clearly understood by those skilled in the art, it is customary to manufacture the loop as a complete component. Before the loop is sent to the assembly line for incorporation in a radio receiver it is assumed that the inductance of the loop falls within predetermined tolerances. In receiving circuits in which the loop is a substantial frequency-determining parameter, it is necessary to maintain the inductance within very close tolerances. It will be appreciated that, once the loop 10 is formed, it would be a difficult, cumbersome, expensive, and time-consuming operation to add or to subtract turns or to rearrange the leads or to separate the loop from the mounting assembly preparatory to final testing of the loop and measurement of its inductance. Nonetheless, those are the expedients

that have heretofore been employed. In accordance with the present invention, there is provided a process by which these time-consuming and expensive operations are dispensed with and more precise quantitative determination of the L of the loop is accomplished.

When the loop assembly comprising the two mounting members, the securing tape strips, the end terminals, and the loop proper has been fabricated, the device is tested with a conventional L-meter. Various types of suitable inductance meters are well known. A conventional meter works on a resonance principle, and it comprises a fixed frequency oscillator having a load circuit, consisting of a variable capacitor, calibrated in terms of inductance, and the inductance under measurement. The variable capacitor is adjusted until resonance is attained, a peaking condition being indicated by an R. F. voltmeter. Since the resonant condition is a mathematical function of the inductance and capacitance parameters in the circuit, the frequency of the applied signal being constant, the capacitor can readily be calibrated in terms of inductance.

Let it be assumed for purposes of discussion that the inductance of an assembly of this type, after measurement by an L-meter, is found to be too low. In accordance with the invention the operator continues to observe the indications of the meter while painting onto the loop a molten mixture comprising powdered iron and impregnating wax. It will be observed that sections of the loop are in registry with apertures 13, 14, 15, and 16, whereby access is permitted for that purpose. The application is made by the use of an ordinary commercially available varnish or paint brush. The deposit of the metallic magnetic material increases the L of the loop, and the operator simply continues the brushing operation and the depositing of such material until the meter reading reaches the desired L value.

Although I do not desire to be limited to any specific proportions, or to any specific powdered magnetic material, satisfactory results have been achieved with a mixture of impregnating wax and iron powder, the proportion of the latter being 25% to 50% by volume, and the temperature of the molten mixture being maintained at 100 to 120 degrees centigrade. The iron powder has a tendency to settle to the bottom of the container, and it is desirable to immerse the applicator deeply therein or to agitate the mixture frequently. Any commercially available impregnating wax such as ceresine is entirely suitable. Any suitable substance which will not destroy the insulation on the loop conductor, which solidifies at ordinary temperatures encountered in operation and has a low melting point may be used in lieu of the preferred wax. Any high permeability iron or ferromagnetic powder will serve as the powder component. Many suitable materials and alloys are known

to the art. Low magnetic retentivity is desired.

The outstanding advantage of this process is that the ferromagnetic material which increases the inductance of the loop is deposited in increments well within the control of a relatively unskilled operator, while the meter reading is observed so that there is no necessity to add or subtract turns or to disturb the loop leads or the mounting assembly in order to make the final adjustment to the desired inductance value. After deposition the molten mixture solidifies into durable masses 31, 32 strongly adhering to the loop proper, and the assembly maintains the desired inductance characteristic throughout the 15 usable life of commercially available radio receivers.

In mass production of loops in accordance with the present invention, an endeavor is made to keep the desired inductance value within or 20 below the specified limits at the end of the winding operation, and special precautions are taken to prevent those values from exceeding such limits. Therefore only those loops which do not 25 conform to the specified inductance value are subjected to the process in accordance with the invention, such process comprising a method for increasing the inductance of a loop.

While there has been shown and described what is at present regarded as the preferred embodiment of the invention, it will be understood by those skilled in the art that various modifications and substitutions of equivalents may be made therein without departing from the spirit and scope of the invention as defined by the claim hereto appended.

Having fully discussed and described my invention, I claim:

The process of increasing the inductance of a loop antenna of insulated wire to a predetermined inductance value which comprises depositing on at least one preselected, isolated bare portion of the loop antenna a hot melt of a low melting-point impregnating wax having dispersed therethrough a ferromagnetic powder, permitting said hot melt to solidify, and thereafter sequentially measuring the inductance of the coated loop antenna and depositing additional increments of said hot melt at other separate and distinct preselected bare portions of said loop antenna until the desired predetermined inductance value is obtained, the total deposit of ferromagnetic powder being an amount sufficient to raise the inductance of the loop antenna to the desired predetermined value.

ALPHONSE CHARLES STELZER.
